GOTTWALT SIEBER, OF PLAUE, GERMANY, ASSIGNOR TO THE FIRM: VOGTLANDISCHE MASCHINENFABRIK (VORMALS: J. C. & H. DIETRICH) AKTIENGESELLSCHAFT, OF PLAUE, GERMANY.

EMBROIDERING MACHINE.

Application filed March 10, 1924, Serial No. 698,308, and in Germany April 9, 1923.

In the case of perpendicular or hanging-over shuttle-paths it is rather difficult to guide the shuttle so that the loop of the thread coming from the needle is with certainty being caught by the point of the shuttle. Although, for this purpose, arrangements have been made to keep the shuttle continuously pressed to the shuttle guide by means of spring tension, these arrangements have shown a drawback in so far, as the spring, keeping in touch with the shuttle, at the same time is increasing the difficulty of sliding the thread over the back of the shuttle, and the needle-thread must be of a certain strength, as otherwise it would be broken by the resisting force occasioned in its passage between the spring and the back of the shuttle.

In order to obviate these drawbacks, provisions are made according to the present invention, that the spring pressing the shuttle against the shuttle guide is not fixed to the shuttle driver, as has hitherto been the case, but to the shuttle guide or to the apertured cloth-plate, so that the shuttle is being pressed against the shuttle guide only for a brief moment, in which the needle-loop is being caught, after which brief moment the loop-thread, however, may be drawn, without being impelled by the spring, over the back of the shuttle quite loosely and freely.

The invention is fully disclosed in the following specification, of which the accompanying drawing is forming a part and is representing a modification of the invention for a vertically arranged shuttle track. In this drawing the separate parts of the invention are designated by suitable reference characters in each of the views, in which:

- 40 Figure 1 is a front view of the shuttle guide,
- Figure 2 a side view of the same, and
- Figure 3 a plan view, while
- Figure 4 is disclosing the shuttle guide after completed removal of the driver bar with the shuttle in its top-position, and Figure 5 is illustrating the identical parts as shown in Fig. 4, but with the shuttle drawn back.
- 50 The apertured stitch plate 2 is fixed to the actual shuttle guide 1 in the well-known manner. The edge of the plate 2 is bent over at 3 in such a manner, that it is made to extend entirely over the shuttle.

In this portion of the stitch plate 2 there has been further provided an aperture 4, into which is entering a rounded-out and bow-shaped portion of a soft plate-spring 6, that is fixed to the outer side of the cloth plate at 5, while the free end of the plate-spring, with the shuttle in its top position, is lying flat against the outer side of the stitch plate.

Along the shuttle guide 1 there is arranged in a guidable manner the driver bar 7, which is provided with a driver pin 8 and with a hook 9 adapted to be swung back around the pivot 11. The said hook is retained in its working position, according to Figures 1-3, by means of plate spring 10. The hook may, however, be swung out laterally, without any further manipulation, by simply raising somewhat the spring 10 according to Fig. 2, so as to enable the removal of the shuttle 12.

The general arrangement has been made in such a manner as to cause the shuttle 12, in its lowest position according to Fig. 5, to be pressed by the spring 6 to the shuttle guide 1 in a manner sufficiently tight, so that the loop of the needle thread, passing out from the stitch plate aperture 15 and placing itself into the plate of the shuttle, will be caught with certainty. As soon, however, as the shuttle has been moved upwards by means of the driver device 7, 8, 9, it separates from the spring 6, so that the needle-thread may slide freely and without hindrance over the back of the shuttle, without being subjected to any additional tension by the spring 6.

The arrangement above described is intended for an embroidery machine adapted to embroider stockings and requiring a high shuttle track set up vertically. There is, however, nothing to prevent the adaption of the principle of the invention also the other shuttle paths not set up absolutely vertical, and more especially to hanging-over shuttle tracks.

In the case of shuttle guides set up side by side very closely, in which the bent over element 3 has been omitted at the stitch plates 2, and where the shuttle is made to be guided by the back side at the adjacent shuttle guide 1, the spring 6 must be fixed to the latter, and for this purpose a suitable take-out must be provided in the said shuttle guide.

Having thus described said invention, what I claim, is:-

1. In a shuttle embroidering machine, in combination: a shuttle and means for guiding it; means for reciprocating said shuttle in said guide-means; a spring attached to the guide-means and so arranged as to be adapted to press the said shuttle against the guide-path provided for it in the said guide means in that position in which the point of the said shuttle is in the neighbourhood of the stitch plate aperture, substantially as set forth. 45
- 10 2. In a shuttle embroidering machine, in combination: a shuttle and means for guiding it, these means being composed of a shuttle guiding member proper and of a stitch-plate so arranged as to co-operate with said guiding member proper in guiding the shuttle; means for reciprocating said shuttle in said guide-means; a spring attached to the guide-means and so arranged as to be adapted to press the said shuttle against the guide-path provided for it in the said guide means in that position in which the point of the said shuttle is in the neighbourhood of the stitch plate aperture, substantially as set forth. 50
- 15 3. In a shuttle embroidering machine, in combination: a shuttle and means for guiding it, these means being composed of a shuttle guiding member proper and of a stitch-plate so arranged as to co-operate with said guiding member proper in guiding the shuttle, said stitch-plate having a bent-over edge and an aperture in this rim; a spring attached to the guide-means and so arranged as to be adapted to press, through said aperture, the said shuttle against the guide-path 55
- 20 4. In a shuttle embroidering machine, in combination: a shuttle and means for guiding it; means for reciprocating said shuttle in said guide-means, and being composed of a reciprocating bar, a pin secured thereto, and a movable hook also attached thereto, the arrangement being such that the shuttle can be grasped between said pin and said hook; a spring attached to the guide-means and so arranged as to be adapted to press the said shuttle against the guide-path provided for it in the said guide means in that position in which the point of the said shuttle is in the neighbourhood of the stitch plate aperture, substantially as set forth. 60
- 25 5. In a shuttle embroidering machine, in combination: a shuttle and means for guiding it, these means being composed of a shuttle guiding member proper and of a stitch-plate so arranged as to co-operate with said guiding member proper in guiding the shuttle; means for reciprocating said shuttle in said guide-means, and being composed of a reciprocating bar, a pin secured thereto, and a movable hook also attached thereto, the arrangement being such that the shuttle can be grasped between said pin and said hook; a spring attached to the guide-means and so arranged as to be adapted to press the said shuttle against the guide-path provided for it in the said guide means in that position in which the point of the said shuttle is in the neighbourhood of the stitch plate aperture, substantially as set forth. 65
- 30 6. In a shuttle embroidering machine, in combination: a shuttle and means for guiding it, these means being composed of a shuttle guiding member proper and of a stitch-plate so arranged as to co-operate with said guiding member proper in guiding the shuttle, said stitch-plate having a bent-over edge and an aperture in this rim; a spring attached to the guide-means and so arranged as to be adapted to press, through said aperture, the said shuttle against the guide-path 70
- 35 7. In a shuttle embroidering machine, in combination: a shuttle and means for guiding it, these means being composed of a shuttle guiding member proper and of a stitch-plate so arranged as to co-operate with said guiding member proper in guiding the shuttle, said stitch-plate having a bent-over edge and an aperture in this rim; a spring attached to the guide-means and so arranged as to be adapted to press, through said aperture, the said shuttle against the guide-path provided for it in the said guide means in that position in which the point of the said shuttle is in the neighbourhood of the stitch plate aperture, substantially as set forth. 75
- 40

In testimony whereof I affix my signature.

GOTTWALT SIEBER.
